(57) **CLAIM**

The ornamental design for a case for electronic communications device, as shown and described.

DESCRIPTION

FIG. 1 is a front perspective view of a case for electronic communications device showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled portion of FIG. 4 to more clearly disclose the appearance of the glitter pattern on the transparent surfaces of the case.

The stippling in the drawing figures depicts the appearance of the glitter pattern on the transparent surfaces of the case. The dot-dash broken line circle in FIGS. 4 and 9 delineates a portion of the case for electronic communications device that is part of the claimed design and that is shown on an enlarged scale in FIG. 9. The dashed broken lines that are adjacent to stippled or shaded regions, and that delineate an unshaded and non-stippled region or an opening, represent the bounds of the claimed design. All other dashed broken lines depict environmental subject matter that forms no part of the claimed design. Broken lines and regions bounded by dashed broken lines that are unshaded and non-stippled form no part of the claimed design.
